UNITED STATES PATENT OFFICE.

CARL RUDQWIST, OF MUNICH, GERMANY.

TWO-STROKE COMBUSTION-ENGINE.

1,239,224.

Specification of Letters Patent.

Patented Sept. 4, 1917.

Application filed December 10, 1914. Serial No. 876,411.

To all whom it may concern:

Be it known that I, CARL RUDQWIST, a citizen of the Swedish Kingdom, residing at Munich, Bavaria, Germany, have invented 5 certain new and useful Improvements in Two-Stroke Combustion-Engines; and I do hereby declare the following to be a full, clear, and exact description of the invention, such as will enable others skilled in the art 10 to which it appertains to make and use the same.

This invention relates to a two stroke cycle combustion engine embodying improvements for enabling the engine to be 15 employed as a high speed engine.

In connection with a two stroke cycle combustion engine having a step piston, it is necessary, while the air is being compressed in the combustion cylinder, to store the 20 scavenging and charging air until the piston has uncovered the channels, which establish communication between the air chamber and the combustion cylinder. The connecting channel between the air pump 25 and the air chamber is frequently shut off by valves, which open when the pressure in the air pump is higher than in the chamber and close when the pressure is lower. Experience has, however, shown that these 30 valves have many disadvantages.

The object of the present invention is to obviate the above-mentioned drawbacks.

A combustion engine constructed according to the present invention is shown in the 35 accompanying drawing.

Figure 1 is a longitudinal section.

Figs. 2 and 3 show the distributing member A in different positions.

The distributing member consists, as 40 shown in Fig. 1, of a cylindrical slide valve A, which derives its reciprocatory movement from an eccentric B and is provided with admission ports P, P₁ and with controlling ports S, C, H; a valve D is provided between the controlling ports C and H and the chamber E is closed above by a valve R.

The eccentric B is disposed relatively to the crank in such a manner that during the 50 compression stroke the distributing member A establishes communication between the step piston pump and the chamber E (see position Fig. 2), the crank being horizontal and the piston having its highest speed. In the end position of the piston (middle position as shown in Fig. 1), the

distributing member A has shut off the suction ports P and P₁ and it is only when the air pump begins to compress the drawn in air, that the passage leading to the air 60 chamber is opened through the medium of the controlling port S.

It is obvious from the position as shown in Fig. 3 that the port S of the air chamber F is closed during the complete suction stroke 65 of the air pump. It is also obvious from Fig. 1 that the connecting channel and the valve top can be formed as air chambers F₁ and E.

It is finally also obvious from the drawings 70 how the air supplied by the air pump is separated into two parts by the distributing member and the valve D respectively i. e. one part for scavenging and another part for charging the working cylinder. This is 75 effected by closing the channel C (Fig. 2) during the complete compression stroke. The air for charging passes through the valve D into the chamber E, while the air for scavenging the working cylinder remains 80 in the chamber F. As the scavenging air must not enter the combustion cylinder under the same high pressure as the charging air, the latter is led through the port C, after the compression stroke, out of the air 85 chamber F to the chamber F₁, where it is stored and reduced to the desired pressure. When the piston has uncovered the port G in the combustion cylinder, the working cylinder is scavenged by the air contained in 90 the chamber F and chamber F₁, respectively. When the piston shuts off the exhaust port G, the port H in the distributing member is opened and the air stored in the air chamber E passes through the channel H₁ 95 into the cylinder. M is a nozzle through which fuel is sprayed into the engine cylinder, and W, W' are the bearings for the engine.

Although I may use any suitable ignition 100 device, to ignite the mixture of fuel and air within the combustion space of the engine cylinder, I have shown a special form of ignition device which consists of a hollow metallic body O, at the head of the cylinder 105 surrounded by an electric heating coil Z. The latter is provided with terminals N, N', for connection to a suitable source of electric current. The ignition device is preferably so positioned as to be surrounded 110 by the water-jacket of the engine cylinder.

In order to maintain a good piston pin

lubrication in a simple, economical and yet perfect manner, which was hitherto always a difficult task in connection with a vertical motor, the step piston is formed as a trough 5 and the piston pin K (Fig. 1) is provided in the piston with a bore and is fitted in such a manner that the oil dropping from the upper cylinder flows in the direction of the arrow to the piston pin bearing through the bore 10 in the piston pin.

I claim as my invention:—

1. In a two stroke cycle combustion engine, the combination of an engine cylinder having a combustion chamber and a pumping chamber therein, a valve casing supported adjacent said engine cylinder and having port openings communicating, respectively, with said combustion chamber and said pumping chamber, a valve slidable 15 in said valve casing, said valve having ports therein adapted to register with the port openings in the casing, means dividing said valve casing into adjacent chambers and permitting passage of air from one chamber to the other in but one direction, and means for reciprocating said valve to successively cause the ports therein to register with the port openings in the valve casing, whereby a charge of scavenging air first 20 passes from one of the chambers in the valve into the combustion chamber and thereafter a second charge of air for admixture with fuel passes from the other chamber in the valve into said combustion chamber.
2. In a two stroke cycle combustion engine, the combination of an engine cylinder having a combustion chamber and a pumping chamber formed therein, a valve casing supported adjacent said engine cylinder and 25 having air admission port openings in communication with said pumping chamber, said valve casing also having a port opening in communication with said combustion chamber and an intermediate scavenging air 30 port opening therein, a valve slidable in said valve casing and having ports adapted to register, respectively, with the port openings in said valve casing, means dividing said valve casing into adjacent chambers and permitting passage of air from one chamber to the other in but one direction, and means for reciprocating said valve to successively cause the ports therein to register with the port openings in the valve casing, whereby a charge of scavenging air first 35 passes from one of the chambers in the valve into the combustion chamber and thereafter a second charge of air for admixture with fuel passes from the other chamber in the valve into said combustion chamber.
3. In a two stroke cycle combustion engine, the combination of an engine cylinder having a combustion chamber and a pumping chamber formed therein, a valve casing supported adjacent said engine cylinder and having air admission port openings in communication with said pumping chamber, said valve casing also having a port opening in communication with said combustion chamber and an intermediate scavenging air 40 port opening therein, a valve slidable in said valve casing and having ports adapted to register, respectively, with the port openings in said valve casing, means dividing said valve casing into adjacent chambers and permitting passage of air from one chamber to the other in but one direction, and means for reciprocating said valve to successively cause the ports therein to register with the port openings in the valve casing, whereby a charge of scavenging air first 45 passes from one of the chambers in the valve into the combustion chamber and thereafter a second charge of air for admixture with fuel passes from the other chamber in the valve into said combustion chamber.
4. In a two stroke cycle combustion engine, the combination of an engine cylinder having a combustion chamber and a pumping chamber therein, a valve casing supported adjacent said cylinder, a valve in said casing divided into adjacent chambers, means for entrapping air in one of said 50 chambers, there being air passages between said valve casing and said engine cylinder, and means for reciprocating said valve whereby a charge of scavenging air first passes into said combustion chamber and thereafter the entrapped air passes into said combustion chamber to admix with fuel therein.
5. In a two stroke cycle combustion engine, the combination of an engine cylinder having a combustion chamber, a pumping chamber, and an intermediate pressure-reducing chamber therein, a valve casing supported adjacent said cylinder, a valve in said casing divided into adjacent chambers, there being air passages between said valve casing and said engine cylinder, and means for reciprocating said valve whereby a charge of scavenging air first passes through said pressure-reducing chamber into said combustion chamber and thereafter the entrapped air passes into said combustion chamber to admix with fuel therein.

gine, the combination of an engine cylinder having a combustion chamber and a pumping chamber therein, a valve casing supported adjacent said engine cylinder, said casing having a pair of air admission port openings therein communicating with said pumping chamber, an intermediate scavenging-air port opening leading to said combustion chamber and an air emission port opening communicating with said combustion chamber, a valve slidable in said casing and having adjacent chambers therein, means for entrapping air in one of said 65 chambers, said valve having ports therein adapted to register, respectively, with the port openings in said valve casing, and means for reciprocating said valve to successively cause the ports therein to register 70 with the port openings in said valve casing, whereby air entering the valve casing through said admission port openings flows through the scavenging-air port opening into the combustion chamber and thereafter 75 the entrapped air flows into said combustion chamber through said air emission port opening.

4. In a two stroke cycle combustion engine, the combination of an engine cylinder having a combustion chamber and a pumping chamber therein, a valve casing supported adjacent said cylinder, a valve in said casing divided into adjacent chambers, means for entrapping air in one of said 80 chambers, there being air passages between said valve casing and said engine cylinder, and means for reciprocating said valve to successively cause the ports therein to register 85 with the port openings in said valve casing, whereby air entering the valve casing through said admission port openings flows through the scavenging-air port opening into the combustion chamber and thereafter the entrapped air flows into said combustion chamber through said air emission port opening.

5. In a two stroke cycle combustion engine, the combination of an engine cylinder having a combustion chamber, a pumping chamber, and an intermediate pressure-reducing chamber therein, a valve casing supported adjacent said cylinder, a valve in said casing divided into adjacent chambers, there being air passages between said valve casing and said engine cylinder, and means for reciprocating said valve whereby a charge of scavenging air first passes through said pressure-reducing chamber into said combustion chamber and thereafter the entrapped air passes into said combustion chamber to admix with fuel therein.

In testimony whereof I hereunto affix my signature in the presence of two witnesses.

CARL RUDQWIST.
